CLAIM

The ornamental design for a pylon sign, as shown and described.

DESCRIPTION

FIG. 1 is a front view of the pylon sign of our design, it being understood that the opposite side not shown is a substantial mirror image thereof, with the pole broken away to indicate indeterminate length.

FIG. 2 is a top view of the pylon sign.

FIG. 3 is a left side view of the pylon sign.

FIG. 4 is a right side view of the pylon sign; and,

FIG. 5 is a bottom view of the pylon sign.
